UNITED STATES PATENT OFFICE

2,501,575

AUTOMATIC TUNING CONTROL CIRCUIT

Madison G. Nicholson, Jr., Snyder, N. Y., assignor to Colonial Radio Corporation, Buffalo, N. Y.

Application February 8, 1944, Serial No. 521,511

10 Claims. (Cl. 250—40)

1

This invention relates to an automatic tuning control circuit, and more particularly to automatic crystal controlled radio transmitters or receivers, although it will be understood that my invention may be applied in other apparatus where automatic tuning of a circuit to any one of a series of predetermined frequencies is desired. Various forms of circuits of this type have been described and claimed in a co-pending application of William S. Winfield, Serial No. 463,775, filed October 29, 1942. In apparatus of this type the circuits are automatically tuned to desired frequencies determined by crystals, and do not involve the setting of mechanical elements, such as pins, contactors, selecting cams, rocker bars, or the like.

In such apparatus there may be provided a variable tuning instrumentality, such as a condenser or variometer operated by an electric motor through a suitable form of reduction gearing. Since the apparatus is particularly useful in airborne radios where space and weight requirements are strict, and since continuous operation is not required, the motor being in operation only when the tuning of the apparatus is changed, it is customary to use a motor which is somewhat smaller and of lighter construction than would be necessary for continuous operation. This apparatus, according to the application above referred to, is arranged so that the motor circuit is closed in the absence of a voltage in the circuit to be tuned and is opened when the voltage in the circuit rises to a predetermined level, so that when the circuit reaches resonance the motor stops operating. On the other hand, if for any reason this predetermined voltage is not generated the motor will continue to operate indefinitely, driving the tuning instrumentality repeatedly through the tuning cycle. This is likely to produce overheating of the motor and may even burn it out.

In accordance with this invention I have provided a circuit which may be said to provide an automatic test of operating conditions once each tuning cycle while the motor is in operation. If this test shows that the apparatus is functioning properly, the circuit will permit continuing operation of the motor for another cycle. If not, the motor is stopped and remains stopped until the trouble is found and remedied.

It is an object of this invention to provide apparatus which will prevent sustained overloading and burnout of the driving motor, which would occur on continuous operation.

It is a further object of this invention to pro-

vide apparatus which will stop the operation of the driving motor in case of certain failure in the associated apparatus, which would otherwise cause the apparatus to continually vary its tuning.

It is still a further object of this invention to provide such apparatus with a minimum of added equipment and parts.

It is still a further object of this invention to provide apparatus of the class described which will stop operation of the tuning motor in case the crystal control elements become defective or removed from their sockets or in case of other trouble which prevents the resonant circuit from building up a voltage.

Still other objects and advantages of my invention will be apparent from the specification.

In the drawing, the single figure is a circuit diagram of one form of apparatus in accordance with my invention.

Referring now more particularly to the drawing, I represents a work circuit which may be a resonator circuit such as the well-known crystal and tube oscillator 15 variably tuned by condenser 9 connected through leads 26 and 27 or other tuning instrumentality. Customarily, a number of crystals 16, 17, 18 are provided, associated with the work circuit I, and some form of selecting means 1a by which the operator may connect the desired crystal into the circuit to fix the frequency of the work circuit. The apparatus may be a radio transmitter or receiver or another form of circuit in which it is desired to provide tuning to any one of a number of previously selected frequencies.

The tuning instrumentality herein referred to as a "condenser," although it may be any other instrumentality, may be driven by any suitable power means, such as motor 7, through suitable reduction gearing 1a, and the condenser 9 may be the means for varying the tuning of work circuit I. In order to control the motor 7 by means of the voltage in the work circuit I, the voltage derived from this circuit may be rectified and passed through a resistance included in a unit 2, and the resulting voltage drop may be impressed between cathode 3a and control electrode 3b of tube 3. Connected to the anode 3c thereof, there may be provided the energizing winding of relay 4, having armature 4a, an energized-position fixed contact 4b, and a deenergized-position fixed contact 4c. The relay 4 controls the opening and closing of the circuit of motor 7 through source 10, through connections made through cam switch 6 driven by cam 8 synchronized with

condenser 9, and having a cam segment 8a corresponding to only a relatively small part of the tuning cycle.

The cam switch comprises the two movable contacts 6a and 6b, the contact 6a cooperating with a first stationary contact 6c and a second stationary contact 6d while the contact 6b similarly cooperates with a first stationary contact 6e and a second stationary contact 6f. Movable contacts 6a and 6b are mechanically connected together, as indicated by the dotted lines, for operation in unison and both engage their respective fixed contacts 6d and 6f at all times during the tuning cycle except when they are moved to close their other respective fixed contacts 6c and 6e by the passage of cam segment 8a under them.

Connections may be provided between fixed contact 4c and fixed contact 6c through lead 20; between fixed contact 4b and fixed contact 6d through lead 21; between movable contact 6b and control electrode 3b through lead 22; and between rectifier and resistance unit 2 and fixed contact 6f through lead 23. Fixed contact 6e may be connected through a series resistor 11 and shunt condenser 12 and through lead 24 to the control grid 15g of the oscillator 15, which may be a part of work circuit 1.

Movable contact 4a is grounded and movable contact 6a is connected to one side of the motor circuit, the other side of which is connected through a suitable power source 10 to ground. The motor energizing circuit is thus completed in either of two ways. The first of these requires that the relay 4 shall not be energized by the control tube 3, so that the relay contacts 4a and 4c are closed, and further requires that the cam segment 8a shall move the contact 6a to engage its fixed contact 6c. The motor circuit is then completed from the source 10 through the closed cam-switch contacts 6a and 6c, conductor 20, and closed relay contacts 4a and 4c. The second manner by which the motor energizing circuit is completed requires that the relay 4 be energized by the control tube 3, to close the relay contacts 4a and 4b, and further requires that the cam 8 operate the movable switch-contact 6a to close its stationary contact 6d. In this case the motor circuit is completed from the source 10 through the cam-switch closed contacts 6a, 6d, the conductor 21, and the closed relay contacts 4a and 4b.

It will be observed that when the cam switch is not actuated by the cam segment 8a, the voltage derived from the work circuit 1 through rectifier and resistance unit 2 is impressed upon the control electrode 3b of tube 3 through fixed contact 6f and movable contact 6b. When cam switch 6b is actuated by cam segment 8a, the control electrode 3b of tube 3 is connected to the oscillator-tube control grid 15g through the switch contacts 6b and 6e, the resistor 11, and the conductor 24.

It will be observed that during the time the control electrode 3b of tube 3 is connected to the oscillator-tube control grid 15g, the motor energizing circuit is completed by the deenergized operating condition of the relay 4 for the reason that the cam segment 8a effects closure of the cam-switch contacts 6a and 6c. It will further be observed that during the time the control electrode 3b of tube 3 is connected to the output circuit of the unit 2, the motor energizing circuit is completed by the energized operating condi-

tion of the relay 4 since the cam 8 now closes the cam-switch contacts 6a and 6d.

With the foregoing description of the apparatus and connections in mind, the operation of the circuit will be readily understood. Assuming that the apparatus is operating on one predetermined frequency and the operator desires to shift to another frequency, he may remove the operating crystal from its socket and insert the new crystal, or if selecting switches are provided as shown, he may operate the selecting switch to select the new frequency. Upon disconnection or removal of the first crystal, the output energy of the work circuit drops to zero, the bias voltage on tube 3 drops to zero, plate current increases, and contact 4a is closed against contact 4b.

If cam switch 6 is positioned at this time to close its contacts 6a, 6d and 6b, 6f, which it is except for a small part of the tuning cycle, then the motor circuit is closed through contact 6d and 6a and the motor operates, varying the tuning of the work circuit 1 through condenser 9. When the work circuit becomes resonant to the new frequency, it begins to deliver output voltage, the bias voltage impressed on tube 3 from the rectifier and resistance 2 reduces the plate current of tube 3 to the point where the relay 4 opens and contact 4a moves out of engagement with contact 4b and into engagement with contact 4c, thus interrupting the motor circuit. The apparatus will remain tuned to the new frequency until the operator changes it again, or until the work circuit stops delivering a voltage for some other reason.

If the crystal or oscillator should suddenly become inoperative, the work circuit would stop delivering voltage to the rectifier and resistance 2, bias voltage on tube 3 would be reduced so that relay 4 would again be energized, and contact 4a would move into engagement with contact 4b, thus closing the motor circuit and operating the tuning condenser 9. This condition would continue, resulting as above explained in possible overheating or burnout of the motor 7, but for the operation of the cam operated switch 6. At one point in the tuning cycle, the cam segment 8a actuates the switch 6, closing movable contact 6a against fixed contact 6c and movable contact 6b against fixed contact 6e as already explained.

With contact 4a against contact 4b as last described, the cam actuation of switch 6 momentarily opens the motor circuit, and the motor stops with the switch contacts 6a, 6c and 6b, 6e in closed position. With the contacts in this position, control electrode 3b of tube 3 is now connected through switch contacts 6b, 6e to the oscillator tube control grid 15g in the work circuit 1. If the oscillator is operating properly, a voltage is being produced (even though the work circuit is not delivering any voltage) which is sufficient to reduce the plate current of tube 3 to the point where the relay 4 becomes degener-ized and contact 4a is permitted to close against contact 4c.

With the contacts of the switch 6 in the position last described, this deenergization of the relay 4 closes the motor circuit and the motor begins operation again and will continue to operate until the cam segment 8a is moved sufficiently that the switch 6 is actuated again to close its contacts 6a, 6d and 6b, 6f. This action now disconnects control electrode 3b from the oscillator grid 15g and restores it to rectifier and resistance 2, and if no voltage is present therein

the plate current of tube 3 will rise and the relay 4 will close its contact 4a against contact 4b, thereby again closing the motor circuit to continue the tuning operation.

If switch 6 happens to have its contacts 6a, 6c and 6b, 6e closed when initial operations are attempted, as when the apparatus is first turned on, as soon as tube 3 heats up and the oscillator begins to oscillate plate current in tube 3 drops because of the bias on its control electrode 3b; the motor circuit is closed by closure of the relay contacts 4a and 4c and the motor begins to operate the tuner. From here on, the operation is as already described.

If, however, when the contacts of cam switch 6 are moved into upper contact position and the control grid 3b connected to the oscillator control grid, there is no voltage on the oscillator control grid (which would be the case if the tube had stopped oscillating due to a defective or missing crystal), the plate current of tube 3 would be of sufficient value to hold contact 4a against contact 4b, thereby keeping the motor circuit open. In other words, the operation of the circuit may be summed up as follows:

Once during each tuning cycle, with the operation of the cam switch, tube 3 tests the oscillating circuit, and if it is operating properly, the motor circuit is closed and operation continues, but if the oscillator is not working, the motor circuit is opened and will remain open until the trouble is found and remedied; so it will be seen that should trouble develop; i. e., should the oscillator tube burn out or should the crystal become inoperative, the motor is prevented from operating. On the other hand, if the oscillator is functioning properly, operation of the motor continues through the next tuning cycle.

In the specification I have explained the principles of my invention and the best mode in which I have contemplated applying those principles so as to distinguish my invention from other inventions, and I have particularly pointed out and distinctly claimed the part, improvement, or combination which I claim as my invention or discovery.

While I have shown and described certain preferred embodiments of my invention, it will be understood that modifications and changes may be made without departing from the spirit and scope of my invention, as will be apparent to those skilled in the art.

I claim:

1. In automatic tuning apparatus, in combination, a frequency determining element, a work circuit including an oscillator for delivering energy limited to a frequency determined by said element, said work circuit having a variable tuning instrumentality power operated means for varying said tuning instrumentality, energy responsive means for interrupting operation of said power means either in response to delivery by said work circuit of a predetermined level of energy or in response to failure of the oscillator to deliver a predetermined level of energy, and means for periodically operatively associating said energy responsive means alternately with said work circuit and with said oscillator.

2. In automatic tuning apparatus, in combination, a frequency determining element, a work circuit including an oscillator for delivering energy limited to a frequency determined by said element, said work circuit having a variable tuning instrumentality, power means for varying said instrumentality, energy responsive means for

interrupting operation of said power means either in response to delivery by said work circuit of a predetermined level of energy or in response to failure of the oscillator to deliver a predetermined level of energy, and means for periodically operatively associating said energy responsive means alternately with said work circuit and with said oscillator, said energy responsive means being arranged to be operatively associated with said oscillator during a small part only of each tuning cycle.

3. In automatic tuning apparatus, in combination, a frequency determining element, a work circuit including an oscillator for delivering energy limited to a frequency determined by said element, said work circuit having a variable tuning instrumentality power operated means for varying said tuning instrumentality, energy responsive means for interrupting operation of said power means either in response to delivery by said work circuit of a predetermined level of energy or in response to failure of the oscillator to deliver a predetermined level of energy, and means for periodically operatively associating said energy responsive means alternately with said work circuit and with said oscillator, said energy responsive means being arranged to be operatively associated with said work circuit during the major part of each tuning cycle and with said oscillator during a small part only of each tuning cycle.

4. In automatic tuning apparatus, in combination, a frequency determining element, a work circuit including an oscillator for delivering energy limited to a frequency determined by said element, said work circuit having a variable tuning instrumentality, power means for varying said instrumentality, energy responsive means for interrupting operation of said power means either in response to delivery by said work circuit of a predetermined level of energy or in response to failure of the oscillator to deliver a predetermined level of energy, and means synchronized with said tuning instrumentality for periodically and alternately connecting said energy responsive means to said work circuit and to said oscillator.

5. In automatic tuning apparatus, in combination, a frequency-determining element, a work circuit including an oscillator for delivering energy limited to a frequency determined by said element, said work circuit having a variable tuning instrumentality, power means for varying said instrumentality, a power control circuit including a thermionic vacuum tube having a current relay in the plate circuit thereof having an armature biased to one contact position and closable to another contact position by the current of said relay, and a cam actuated switch having at least two contacts closable in individual ones of a first and a second operating position of said switch and arranged in circuit with said power means and with said armature for preparing said power circuit for closure either in said first or said second operating position of said cam switch, whereby closure and opening of said power circuit may be controlled by said thermionic relay, and a second set of contacts on said cam switch and effective in said first and said second operating position thereof for selectively connecting the control electrode of said thermionic vacuum tube to the output of said work circuit or to said oscillator, said cam switch being synchronized with said tuning instrumentality.

6. In automatic tuning apparatus, in combination, a frequency-determining element, a work circuit including an oscillator for delivering en-

ergy limited to a frequency determined by said element, said work circuit having a variable tuning instrumentality, power means for varying said instrumentality, a power control circuit including a thermionic vacuum tube having a current relay in the plate circuit thereof, said relay having an armature biased to one contact position and closable to another contact position by the current of said relay, and a cam switch having a first set of fixed and movable contacts preparing said power control circuit for closure on either said one or said other contact positions of said relay armature, and a second set of fixed and movable contacts for selectively connecting the control circuit of said thermionic relay to the output of said work circuit or to said oscillator respectively, said cam switch being synchronized with said tuning instrumentality, whereby in one position of said cam switch predetermined current in said relay causes closure of said power circuit while in the other position of said cam switch predetermined current in said relay causes opening of said power circuit.

7. In automatic tuning apparatus, in combination, a frequency-determining element, a work circuit including an oscillator for delivering energy limited to a frequency determined by said element, said work circuit having a variable tuning instrumentality, power means for varying said instrumentality, a power control circuit including a thermionic vacuum tube having a current relay in the plate circuit thereof, said relay having an armature biased to one contact position and closable to another contact position by the current of said relay, and a cam switch having a first set of fixed and movable contacts preparing said power control circuit for closure on either said one or said other contact positions of said relay armature, and a second set of fixed and movable contacts for selectively connecting the control circuit of said thermionic relay to the output of said work circuit or to said oscillator respectively, said cam switch being synchronized with said tuning instrumentality, whereby in one position of said cam switch predetermined current in said relay causes closure of said power circuit while in the other position of said cam switch predetermined current in said relay causes opening of said power circuit, said cam switch being arranged to prepare said power circuit for closure through said other contact of said relay during the major part of the tuning cycle.

8. In automatic tuning apparatus, in combination, a frequency-determining element, a work circuit including an oscillator for delivering energy limited to a frequency determined by said element, said work circuit having a variable tuning instrumentality, power means for varying said instrumentality, a power control circuit including a thermionic vacuum tube having a current relay in the plate circuit thereof, said relay having an armature biased to one contact position and closable to another contact position by the current of said relay, and a cam switch having a first set of fixed and movable contacts preparing said power control circuit for closure on either said one or said other contact positions of said relay armature, and a second set of fixed and movable contacts for selectively connecting the control circuit of said thermionic relay to the output of said work circuit or to said oscillator respectively, said cam switch being synchronized with said tuning instrumentality, whereby in one position of said cam switch predetermined current in said relay causes closure of said power circuit while in the

other position of said cam switch predetermined current in said relay causes opening of said power circuit, said cam switch being arranged to prepare the power circuit for closure on said one contact of said relay during a small part only of each tuning cycle.

9. In automatic tuning apparatus, in combination, a frequency-determining element, a work circuit including an oscillator for delivering energy limited to a frequency determined by said element, said work circuit having a variable tuning instrumentality, power means for varying said instrumentality, a power control circuit including a thermionic vacuum tube having a current relay in the plate circuit thereof, said relay having an armature biased to one contact position and closable to another contact position by the current of said relay, and a cam switch having a first set of fixed and movable contacts preparing said power control circuit for closure on either said one or said other contact positions of said relay armature, and a second set of fixed and movable contacts for selectively connecting the control circuit of said thermionic relay to the output of said work circuit or to said oscillator respectively, said cam switch being synchronized with said tuning instrumentality, whereby in one position of said cam switch predetermined current in said relay causes closure of said power circuit while in the other position of said cam switch predetermined current in said relay causes opening of said power circuit, said cam switch being arranged to prepare said power circuit for closure through said other contact of said relay during the major part of the tuning cycle and for closure on said one contact of said relay during a small part only of each tuning cycle.

10. In automatic tuning apparatus, in combination, a frequency-determining element, a work circuit including an oscillator for delivering energy having a frequency determined by said element, said work circuit including a variable tuning instrumentality, power means for varying said instrumentality, and a control system for controlling the energization of said power means, said system including means operating in synchronized relation with said tuning instrumentality for selectively coupling said control system during one portion of each tuning cycle to the output of said work circuit and during another portion thereof to said oscillator, and means also operating in synchronized relation with said tuning instrumentality for reversing as between said one and said other portion of said each tuning cycle the mode of control effected by said control system over the energization of said power means.
